UNITED STATES PATENT OFFICE.

HENRY S. SPACKMAN, OF ARDMORE, AND ELLIS W. LAZELL, OF PHILADELPHIA, PENNSYLVANIA, ASSIGNORS TO THE HENRY S. SPACKMAN ENGINEERING COMPANY, OF PHILADELPHIA, PENNSYLVANIA, A CORPORATION OF NEW JERSEY.

STACK-KILN.

No. 874,631.

Specification of Letters Patent.

Patented Dec. 24, 1907.

Application filed July 27, 1907. Serial No. 385,859.

To all whom it may concern:

Be it known that we, HENRY S. SPACKMAN, a resident of Ardmore, in the county of Montgomery and State of Pennsylvania, and ELLIS W. LAZELL, residing at Philadelphia, county of Philadelphia, and State of Pennsylvania, citizens of the United States, have made certain new and useful Inventions Relating to Stack-Kilns, of which the following is a specification, taken in connection with the accompanying drawings, forming a part of the same.

This invention relates especially to stack kilns for the burning of lime, cement or other material, and in which by the heat regulation and successive supplying of the air to the combustion chamber and kiln an efficient long flame is produced, the heat of the burned material being largely recovered in heating the air supplied.

In the accompanying drawings showing an illustrative embodiment of this invention and in which the same reference numeral refers to similar parts in the several figures.

Figure 1 is a partial vertical section, and Fig. 2 is a transverse section taken substantially along the line 2--2 of Fig. 1.

The kiln shaft 21 may have a lining 8 of bricks of suitable character within the shaft body 9 which may be, of course, inclosed in a metallic shell, as is usual. The upper part 19 of the shell supports the charging door 31 which may be open so as to engage the support 32 when supplying materials to the throat 20. As the kiln is preferably operated under suitable suction the goose neck 17 may have its lower end supported in a substantially central location by any desired means so as to conduct the gases into the suction pipe 18 which may be connected with a high stack or other exhaust means.

As indicated the shaft may be supported upon a suitable masonry base having outer lateral concrete or brick walls 1 and also the inner walls indicated so that suitable ash chutes 2 are provided as well as an internal air chamber 4. The cooler 7 is preferably in line with the kiln shaft and may be provided at its lower end with a metallic discharge cone 6 having external corrugations or ribs, if desired. The discharge of burned material from the opening 28 is controlled by the gate 29 or otherwise, the material being delivered

into cars or other conveying means and passing through the arch 5. Any desired number of heating furnaces may be arranged adjacent the kiln shaft, several separate furnaces being preferably employed so as to give more accurate control of the heat.

As indicated in Fig. 1, each furnace preferably comprises a suitable grate to which access may be had by the firing door 14, the bridge wall 12 being provided with a suitable opening 13, if desired, and having its inner face adjacent the stack relieved or inclined in the direction indicated to such extent as gives the proper clearance and prevents the material in the shaft from entering the furnace throat. Below the grate a suitable ash-pit is provided to which access may be had by the ash-pit door 15 and a removable ash cover 16 closes an opening into the ash chute 2 so that ashes may readily pass down this chute and be removed from time to time through the opening 3.

Suitable flues and passages are preferably provided so that the air entering the arch 5 or other opening into the air chamber becomes highly heated by the heat derived from the burned material in the cooler and from the adjacent walls of the chamber. This air is still further heated as it passes up through the annular portion 30 of the air chamber. The air is then divided into the proper quantities of initial air which is supplied to the ash pits of the furnaces and passing through the fuel bed produces the proper combustion of the fuel therein so that the furnace preferably has a producer action and supplies the hot gaseous products of partial combustion of the fuel through the throat between the bridge wall and the combustion arch where the secondary air supplied through the ports 22, if desired, assists the complete combustion of the fuel in connection with further supplemental air entering the kiln shaft through the ports 26.

Any desired means, such as suitable dampers, injectors or other draft devices may be used to properly control the volume and temperature of the air supplied in these various ways. The initial air, for example, may pass through the flue 35 from the air chamber and be forced into the ash-pit by a suitable injector 25 supplied by a blast of air, steam or gas at the desired regulated pres-

sure and this injector jet may also carry in the desired proportion of atmospheric air by the regulation of the air damper 33. In this way the combustion of the fuel on the grate 5 may be accurately regulated preferably so as to supply a large volume of heated products of partial combustion comprising carbon-monoxid and hydrocarbons to the kiln shaft. The supplemental air may be supplied in the 10 desired volumes by similar regulating devices, a suitable injector 23 being shown as located in the passage adjacent the port 22 so as to admit, if desired, regulated quantities of atmospheric air and force this, together with the heated air from the air chamber below through the secondary parts 22, as shown in Fig. 2. Further supplies of supplemental air may be forced into the kiln shaft through the port 26 located still higher up by 15 similar means, the air rising through the flues 36 which may be provided with the injectors 43, if desired, the air being distributed by the passage 27 to the desired number of supplemental ports 26. In this way, 20 a very perfect control of the combustion and kiln temperature may be had and where lime is burned the flame is preferably regulated so as to produce a voluminous flame of moderate temperature substantially filling the 25 entire cross-section of the kiln shaft for a considerable distance above the heating zone adjacent the separate furnaces and effecting the burning of the lime in the desired uniform manner. By the regulation of the 30 temperature of the air supplied to the ash-pits and fuel beds the temperature and composition of the gases thereby produced can be regulated and the temperature of these gases can be, if desired, still further modified by the 35 use of a suitable proportion of tempering gas such as steam which may, if desired, be used as the injecting jet, although this is not necessary in most cases.

As indicated in Fig. 2 the kiln shaft may be 40 given a generally oval section at its lower end adjacent the furnaces and may flare outward in an upward direction so that it is more nearly circular at the upper portion of the stack adjacent the throat.

Having described this invention in connection with an illustrative embodiment thereof, to the details of which disclosure the invention is not, of course, to be limited, what is claimed as new and what is desired to be 55 secured by Letters Patent is set forth in the appended claims.

1. In stack kilns, a kiln shaft provided with a goose neck and suction pipe adjacent its upper end to carry off the kiln gases, a 60 plurality of separate producer furnaces communicating with the kiln shaft, each of said furnaces being provided with a grate, a combustion arch and a coöperating bridge wall having an opening substantially in line with 65 said grate and having a relieved inner face

adjacent the stack to prevent the burned material entering the furnace throat, a cooler substantially in line with and receiving the burned material from the kiln shaft, said cooler having a corrugated metallic discharge cone provided with a gate, a substantially inclosed air chamber around said cooler, flues conducting the heated air from said air chamber to said ash-pits, separate supplemental flues from said air chamber 70 communicating with secondary ports in the kiln stack adjacent said furnaces and communicating with supplemental ports in the kiln stack above the level of said furnaces and blast devices in said flues to control the 75 air-blast passing therethrough.

2. In stack kilns, a kiln shaft provided with a suction pipe adjacent its upper end to carry off the kiln gases, a plurality of separate producer furnaces communicating with the kiln shaft, each of said furnaces being provided with a grate, a combustion arch and a coöperating bridge wall having a relieved inner face adjacent the stack, an inclosed ash-pit below said grate having an 80 ash-chute below the same and closed by an ash-pit door, a cooler substantially in line with and receiving the burned material from the kiln shaft, said cooler having a corrugated metallic discharge cone, a substantially 85 inclosed air chamber around said cooler, flues conducting the heated air from said air chamber to said ash-pits, separate supplemental flues from said air chamber provided with ports entering the kiln stack adjacent said furnaces, injectors in said flues to 90 control the air blast passing therethrough and means to admit external air to said flues.

3. In stack kilns, a kiln shaft having a plurality of communicating separate producer furnaces, each of said furnaces being provided with a grate, a combustion arch and a coöperating bridge wall having a relieved inner face adjacent the stack, an inclosed ash-pit below said grate, a cooler substantially 100 in line with and receiving the burned material from the kiln shaft, a substantially inclosed air chamber around said cooler, flues conducting the heated air from said air chamber to said ash-pits, separate supplemental flues from said air chamber communicating with ports entering the kiln stack adjacent and above the furnaces and means 105 to control the air blast passing through said flues.

4. In stack kilns, a kiln shaft having a plurality of communicating separate producer furnaces, each of said furnaces having a constricted throat, means to prevent the access of the burned material to said throat and an 110 inclosed ash-pit, a cooler below said furnaces to receive the burned material from the kiln shaft, a substantially inclosed air chamber around said cooler, and means to force heated air from said air chamber to said ash- 115

pits and to said kiln shaft adjacent and above the throats of said furnaces in regulated quantities.

5. In stack kilns, a kiln shaft having a plurality of communicating separated producer furnaces, each of said furnaces having a constricted throat, means to prevent the access of burned material to said throat and an inclosed ash-pit, a cooler constituting a continuation of said kiln shaft and substantially inclosed to form an air-heating chamber and means to supply air of regulated temperature and amount from said air chamber to said ash-pits and to the kiln shaft adjacent or above the throats of said furnaces.

6. In stack kilns, a kiln shaft having a separate furnace communicating with said kiln shaft through a constricted throat, a substantially inclosed ash-pit for said furnace and means to prevent the access of burned material to said throat, a cooler having heat-diffusing walls extending below said kiln shaft and receiving the burned material therefrom, a substantially inclosed air chamber around said cooler and means to supply regulated quantities of heated air from said cooler to said ash-pit and to the kiln shaft adjacent to or above the throat of said furnace.

7. In stack kilns, a kiln shaft having a separate furnace communicating with said shaft through a constricted throat, a substantially inclosed ash-pit for said furnace, a substantially inclosed air chamber through which the burned material passes and means to supply heated air from said air chamber to said ash-pit and to the kiln shaft adjacent the throat of said furnace.

8. In stack kilns, a kiln shaft having a separate furnace communicating with said shaft through a constricted throat, a cooler substantially in line with and receiving the burned material from said kiln shaft, a substantially inclosed air chamber surrounding said cooler and means to supply heated air from said air chamber to the kiln shaft adjacent or above the throat of said furnace.

9. In stack kilns, a kiln shaft having separate heating means communicating therewith, a cooler below said heating means and receiving the burned material from said kiln shaft, a substantially inclosed air chamber surrounding said cooler and means to supply heated air from said air chamber to said kiln shaft adjacent or above said heating means.

55 10. In stack kilns, a kiln shaft having sepa-

rate heating means communicating therewith, a substantially inclosed air chamber below said heating means through which the burned material passes and is thereby cooled and means for supplying heated air from said air chamber to said kiln shaft adjacent or above said heating means.

11. In stack kilns, a kiln shaft having a separate heating furnace communicating with said shaft through a constricted throat, means to prevent the access of burned material to said throat, an inclosed ash pit for said furnace, a cooler below said furnace to receive the burned material from the kiln shaft, a substantially inclosed air chamber around said cooler and means to force heated air in regulated quantities from said air chamber to said kiln shaft adjacent the throat of said furnace.

12. In stack kilns, a kiln shaft having a plurality of separate furnaces communicating therewith, a cooler below said furnaces to receive the burned material from the kiln shaft, a substantially inclosed air chamber around said cooler and means to force heated air in regulated quantities from said air chamber to said kiln shaft adjacent or above the throats of said furnaces.

13. In stack kilns, a kiln shaft having a separate heating furnace communicating therewith, a suction pipe communicating with said shaft adjacent its upper end and having its depending intake end located below the normal level of material in said kiln shaft and means to supply heated air to the kiln shaft adjacent the mouth of said furnace.

14. In stack kilns, a kiln shaft having a plurality of separate heating furnaces communicating therewith, each of said furnaces being provided with a grate, a combustion arch, a co-operating bridge wall having a relieved inner face adjacent the stack and an inclosed ash-pit below said grate, a cooler substantially in line with and receiving the burned material from the kiln shaft, a substantially inclosed air chamber around said cooler and flues conducting the heated air from said air chamber to said ash-pits and to the kiln stack adjacent or above the throats of said furnaces.
